UNITED STATES PATENT OFFICE.

HERBERT M. DE WITT, OF DENVER, COLORADO.

HYDRAULIC AIR-COMPRESSOR.

1,353,897.

Specification of Letters Patent. Patented Sept. 28, 1920.

Application filed July 30, 1919. Serial No. 314,192.

To all whom it may concern:

Be it known that I, HERBERT M. DE WITT, a citizen of the United States, residing at Denver, in the county of Denver and 5 State of Colorado, have invented certain new and useful Improvements in Hydraulic Air-Compressors, of which the following is a specification.

This invention relates to hydraulic air compressors and its object is to provide an 10 apparatus for the compression of air which operates automatically by a head of water falling from an elevated source.

My invention is particularly adapted for 15 use at mines and other isolated milling and manufacturing plants to produce the air under pressure needed for the operation of rock drills and other machines without cost of power.

20 With the above and other objects in view all of which will appear in the course of the following description my invention consists of the construction and combination of devices shown in the accompanying drawings 25 in which—

Figure 1 is a sectional elevation of my improved air-compressing apparatus, and

Fig. 2, a side elevation of the valve which 30 controls the water flow to and from the companion units of the apparatus.

Referring to the drawings by numerical reference characters, my improved compressor is composed of two stationary, preferably cylindrical containers 5 and 6 which 35 are alike in size and construction and which may be installed upon any suitable foundation or supporting structure.

A rotary valve 7 in a ported housing 8 controls the flow of water falling through a 40 stand pipe 9 connected with an elevated source of supply, to and from the containers.

The valve-housing has to this end a port 10 which connects with the stand-pipe, ports 11 and 12 at opposite sides thereof, which 45 are respectively connected with corresponding ends of the two cylinders through the medium of conduits 13 and 14 and ports 15 and 16 at opposite sides of the other ports which connect with spouts 17 and 18 which 50 deliver the water discharged from the cylinders into an automatic valve reversing element hereinafter to be described.

The ports of the housing are equidistantly spaced to connect in pairs with peripheral 55 channels 19 and 20 in the rotary valve which in the operation of the apparatus is moved

to two positions to alternately connect each cylinder with the stand-pipe for the intake of water and with one of the discharge-spouts for the exhaust of water it has previously received, reversely with relation to 60 the other cylinder.

Each cylinder has at its end opposite to that connected with the respective water conduit, an outlet-opening and an inlet open- 65 ing.

The outlet openings of the containers are connected with a reservoir for the storage of air under pressure, by means of branches 19 and 20 of a common delivery conduit 21, 70 each provided with a check-valve 22 which prevents the return flow of air from the reservoir and thereby maintains it at a pre-determined pressure.

The passage of air into the cylinder 75 through the intake openings is likewise controlled by check-valves 23 in pipes 24 and 25, which prevent the escape of air through said openings during compression.

The automatic valve reversing element 80 hereinbefore referred to consists of a teeter-trough 26 pivoted as at 27 and disposed to receive the water discharged through the spouts 17 and 18 of the valve housing, at opposite sides of the vertical plane passing 85 through its axis of oscillation.

The trough is divided by a central transverse partition 28 into two sections 29 and 30 which diverge at opposite sides of its pivotal axis and which are relatively arranged so that one extends in a substantially horizontal position to receive the water discharged through the superposed spout of the valve, while the other slants downwardly to discharge the water it had previously received. 95

The trough sections have at their outer ends outlets controlled by valves 31 and 32 which in the operation of the device are constantly in either a partially open or wide- 100 open position.

The water-receiving section of the trough is supported in its horizontal position upon an arm of one of two levers 33 which are fulcrumed as at 34 and which carry at the 105 ends of their opposite arms, counterbalancing weights.

The weights are preferably supplied by the contents of boxes 35 formed in the outer ends of the levers, which may be lessened or increased to permit of ready and accurate regulation of the periods in the operation of 110

the apparatus at which the positions of the valve are reversed.

The levers carry at the ends of their arms which support the ends of the trough, pivoted spring-held trips 36 which permit of the return movement of the trough past the lever ends when its position is reversed.

The oscillating motion of the trough is communicated to the rotary valve through the medium of a crank arm 37 on the valve and a pair of chains 38 which connect said arm with the end of the trough and run in opposite directions over sheaves 39 and 40 on a relatively stationary support.

In the operation of the compressor, the containers are alternately placed in communication with the elevated source of supply for the compression of air by the inflow of water, the compressed air being forced into the reservoir past the check-valve 22 and stored for future use.

While the one unit is thus operating to compress the air, the water previously admitted to the companion-unit is discharged and new air enters through the intake-opening past the check-valve 23 which controls the same.

The discharged water is employed to operate the trough of the valve reversing element which when a predetermined quantity of water has accumulated, overbalances the weighted trip-lever which held its receiving section in position and thereby reverses the position of the controlling valve.

In the position of the parts shown in the drawings, the unit 6 is in communication with the stand-pipe 9 through the connection of the ports 10 and 12 in the valve housing by the channel 20 of the rotary valve, and the other unit is connected with the respective discharge spout 17 by the connection of the ports 11 and 15 through the medium of the other channel 19.

The water entering the cylinder under a head, compresses the air in the upper end thereof and forces it past the check-valve 22 into the pipe 21 connected with the reservoir.

The water contained in the other cylinder is at the same time discharged through the spout 17 while new air enters the cylinder past the check valve 23.

The discharged water falls into the section 29 of the teeter-trough supported upon the respective lever, and inasmuch as the water is supplied faster than it can flow through the open valve, it accumulates in the section until the section 30 is drained, when the trough by movement about its pivotal axis, reverses the position of the valve, it being understood that while one of the sections of the trough is being filled the other is being emptied through the open valve at its lower end.

It will thus be seen that contingent on a

constant supply of water under a sufficient head to produce the desired degree of compression, the apparatus operates continuously to compress air and store it in a reservoir in quantities alternately supplied by the companion-units and that the operation takes place without requiring attention other than the proper lubrication of the moving parts.

The operation of the compressor is started by reversing the position of the valve by hand after its housing has been placed in communication with the source of water supply. The valve thus adjusted admits water to the empty container while the other one empties into the elevated part of the teeter-trough and after the latter is moved about its pivot by the accumulated water, the operation is automatically continued as hereinbefore explained.

Having thus described my invention what I claim and desire to secure by Letters-Patent is:

1. A hydraulic air-compressor comprising in combination with a source of water under pressure, two containers each having at one end a valve-controlled air-inlet and a valve-controlled air-outlet, a valve controlling a flow of water to and from the opposite ends of the containers and adapted to alternately place the containers in communication with the source, and mechanism for the operation of the valve by the discharge of water from the containers.

2. A hydraulic air-compressor comprising in combination with a source of water under pressure, two units each adapted for the compression of air by water pressure, a water-supply-conduit, a valve-housing having discharge-ports, ports connecting with the units, and a port connected with the supply-conduit, a valve movable in said housing and adapted to connect said ports in pairs whereby to place each unit alternately in connection with the conduit and one of the discharge ports, reversely with relation to the other unit, and an element operating by water discharged through the discharge ports of the valve-housing, to periodically reverse the position of the valve.

3. A hydraulic air-compressor comprising in combination with a source of water under pressure, two units each adapted for the compression of air by water pressure, a water-supply conduit, a valve-housing having discharge-ports, ports connecting with the units, and a port connected with the supply-conduit, a valve movable in said housing and adapted to connect said ports in pairs whereby to place each unit alternately in connection with the conduit and one of the discharge-ports, a pivoted trough having sections disposed to respectively receive the water from the discharge ports of the valve housing, unbalanced trip levers

adapted to hold the sections in a water-receiving position, and means for reversing the positions of the valve by the pivotal movement of the trough.

5 4. A hydraulic air-compressor comprising in combination with a source of water under pressure, two units each adapted for the compression of air by water-pressure, a valve controlling a flow of water to and

from the units and adapted to alternately 10 place the units in communication with the source, and mechanism for the operation of the valve by the discharge of water from the units.

In testimony whereof I have affixed my 15 signature.

HERBERT M. DE WITT.
